DISPLAY COUNTER APPARATUS

Application filed May 14, 1932. Serial No. 611,347.

My invention relates to display counters and more particularly to counters which are partitioned into a number of suitable compartments for the display of merchandise. 5 In the merchandising of small articles such as notions, hardware, small toys and the like, the common practice is to display such articles on counters which are provided with compartments suitable in size to accommodate the various articles. One form 10 of display counter which is at present widely used employs a great number of wooden boxes which are positioned bottom-side-up on the counters. Sheets of glass are vertically supported between adjacent boxes to form the desired compartments of the counter. The boxes are urged into supporting 15 relation with the glass partitions by forcing strips of cardboard, or the like, between the outer walls of the counter and the boxes which are positioned adjacent these walls. After wedging a number of rows of these boxes into firm supporting relation with the vertical glass partitions, considerable strain 20 is exerted against the outer walls of the counter which often results in tearing these walls loose from the top of the counter. An additional undesirable feature of this type of construction is that a different sized box 25 is required for each size of compartment, and care must be exercised in placing these boxes on the counters as each transverse row of boxes must be substantially equal in length.

An object of my invention is to provide a 30 simple, inexpensive apparatus by means of which different sized compartments can be quickly and easily formed on a display counter.

Another object of my invention is to provide 35 suitable compartment forming apparatus for display counters which can be used without changing or adding to the counters which are in use at present.

A further object of my invention is the provision of a compartment forming apparatus for display counters which is self-contained and one which does not exert abnormal strains upon the counter.

A still further object of my invention is 40 the provision of suitable means for sup-

porting an auxiliary display tray in elevated relation to the display counter of my invention.

Other objects and advantages will be made manifest in the following description 55 taken in connection with the accompanying drawings, in which:

Fig. 1 is a fragmentary perspective view of the apparatus of my invention as it appears when set up on a display counter. 60

Fig. 2 is a vertical sectional view taken on the line 2—2 of Fig. 1.

Fig. 3 is a perspective view of a partition supporting clip of my invention shown in 65 connection with a fragment of one of the pans of my invention.

Fig. 4 is a fragmentary plan view of a portion of the compartment forming apparatus of my invention.

Figs. 5 and 6 are fragmentary sectional 70 views illustrating the operation of a portion of my invention.

Fig. 7 is a detail perspective view of one of the tray supporting standards shown in 75 Fig. 1.

Fig. 8 is a perspective view of one of the spacers included in my invention.

Fig. 9 is a vertical sectional view illustrating the applied position of the spacer shown 80 in Fig. 8.

Fig. 10 is a fragmentary perspective view of a modified tray supporting standard of my invention.

Referring specifically to the drawings, a 85 compartment forming apparatus 10, comprising a preferred embodiment of my invention, is shown in Fig. 1, this apparatus including a suitable counter 11, a plurality of inverted pans 12, partitions 13 extending transversely with respect to the counter 11, partition supporting clips 14, longitudinal partitions 15, and auxiliary trays 16.

The counter 11 is of conventional design 90 having a suitable base 20, a top 21, end walls 22 and front and back walls 23 and 24, respectively. The walls 22, 23, and 24 are secured to the top 21 and extend above the top 95 to form a shallow rectangular compartment which is coextensive with the area of the 100

top 21. Permanently secured to the inner side of the counter walls 22, 23, and 24 by suitable brackets 25 are glass plates 26.

The pans 12, shown in Figs. 2 and 3, are preferably formed of one piece of metal to provide a top 27, end walls 28 and side walls 29. Punched through the top 27 of each of the pans 12 are two rows of slots 30, these rows being positioned parallel and in close proximity with the side walls 29 of the pans 12. The slots 30 are equally spaced as shown in Fig. 4. At each corner of the pans 12 a slot 31 is provided, these slots being positioned at right angles to the slots 30. It will be noted in Fig. 4 that when the pans 12 are spaced apart sufficiently to receive one of the transverse partitions 13 that the distance between the slots 31 of adjacent pans is equal to the space between any two of the slots 30. The overall length of the pans 12 is slightly less than the distance between the inner surfaces of the front and back walls 23 and 24 of the counter 11 so as to allow the pans to be placed transversely upon the top 21 of the counter.

The transverse partitions 13 are preferably of glass and are equal in length to the pans 12. The height of the partitions 13 is equal to the height of the pans 12 plus the depth of the compartments to be formed on the upper surfaces of the pans 12, as shown in Fig. 2.

The partition supporting clips 14, shown in Figs. 1 to 6 inclusive, are formed of sheet metal, each clip being formed from a single piece of metal to provide a pair of horizontal base flanges 35, parallel, vertical walls 36 joined by a semi-circular back wall 37, and depending, parallel hooks 38. The walls 36 are spaced apart sufficiently to firmly receive the ends of the partitions 13 or 15. The hooks 38 are cut so as to provide points 40 on their lower edges, and open slots 41 as shown in Figs. 3, 5 and 6 the lower edges of the slots 41 being slightly inclined to provide cam faces 42. It will be noted that the distance between the hooks 38 and the clip 14 is equal to the distance between the slots 30 of the pans 12.

The longitudinal partitions 15 are also preferably of glass and are substantially equal in length to the width of the pans 12. The height of the partitions 15 is equal to the depth of the compartments to be formed on the upper surfaces of the pans 12 as shown in Fig. 2.

The auxiliary tray 16 shown in Fig. 1, and fragmentarily shown in Fig. 10, includes a standard 44 which is formed of one piece of metal to provide horizontal base flanges 45, depending, parallel hooks 46, vertical parallel walls 47, and a vertical tubular extension 48, which is provided with a vertical slot 50. The standard 44 is identical

with the aforescribed clip 14 with the exception that the standard is provided with the tubular extension 48. Removably secured to the upper end of the tubular extensions 48 of the standards 44 are horizontal tray supporting yokes 55 provided at opposite ends thereof with return bent portions 56 shown clearly in Fig. 7. The yokes 55 are centrally provided with downwardly extending pins 57 which fit snugly within the upper end of the standards 44. The standards 44 are adapted to support an auxiliary tray 60 in elevated relation to the display counter, as shown in Fig. 1.

Referring particularly to Fig. 10, I have shown therein a modified auxiliary tray 75 which includes a standard 76 which is identical with the standard 44, excepting that a hole 77 is provided on the tubular extension of the standard 76. Removably secured to the top of the standard 76 is a yoke 78 provided with a brace 79, the lower end of which is received by the hole 77 in the standard 76. The standards 76 can be used to support the ends of the transverse partitions 13, as shown in Fig. 10, in addition to supporting a tray 80 which is identical with the aforescribed tray 60.

Referring particularly to Fig. 8, I have shown therein a yieldable spacer 64 which includes a vertical back portion 65, a horizontal flange 66, and a return bent portion 67 which extends upwardly from the lower edge of the back portion 65. The height of the spacer 17 is equal to the height of one of the pans 12. These spacers are provided for the purpose of taking up any slack that might exist between the end walls 22 of the counter and the pans 12 which lie adjacent these walls. This slack condition occurs whenever one or more of the transverse partitions 13 is omitted from the assembly for the purpose of providing double-width compartments on the counter 11. The spacers 17 are positioned as shown in Fig. 9, it being noted that the resilient portion 67 and the back portion 65 exert a continuous pressure against the walls of the adjacent pans 12, and that the space occupied by the spacer 17 is covered over by the horizontal flange 66 of the spacer 17.

The preferred procedure of assembling the apparatus 10 of my invention upon the counter 11 is as follows:

The required number of pans 12 to cover the top 21 of the counter 11 are laid transversely across the counter with the tops 27 of the pans uppermost. As it is customary to cover the top of the counter 11 with sheets of paper, I provide paper sheets 70 which are equal in size to the tops of the pans 12. These sheets are properly placed upon the pans 12, and the pans are secured together in spaced relation by the end pairs of clips 14, the hooks 38 of which extend

into the slots 31 of these pans. The manner of applying one of the clips 14 to a pan 12 to support a partition 15 is shown in Figs. 5 and 6. The hooks 38 of the clip 14 are forced through the paper sheet 70 and through two of the slots 30 of the pan 12 as shown in Fig. 5, it being noted that the sharp points 40 on the lower edge of the hooks 38 permit easy insertion of the hooks 10 through the paper. As shown in Fig. 6, the clip 14 is now moved in the direction of the arrow, this causing the cam faces 42 of the hooks 38 to engage the under surface of the top 27 of the pan 12 and the flanges 35 of 15 the clip are drawn into firm contact with paper sheet 70 and the top surface of the pan 12. Adjacent pans 12 are adapted to be locked together by pairs of clips 14 by inserting the hooks 38 thereof into slots 31 20 in the same manner as just described for inserting these into slots 30.

After the adjacent corners of the pans 12 have been thus connected by clips 14 the transverse partitions 13 are inserted between 25 the opposed walls 29 of these pans as shown in Fig. 4. It is clear that the clips 14 are held in locked relation with the pans 12 by the partitions 13 and 15 due to the contact of the ends of the partitions with the 30 back walls 37 of the clips.

The tray supporting standards 44 are adapted to be positioned upon the counter 11 in any desired position by mounting the standards 44 upon the pans 12 in a manner 35 identical with the mounting of the clips 14 on the pans. After the standards 44 are suitably mounted on the pans 12 the tray supporting yokes 55 are mounted on the standards by inserting the pins 57 of the 40 yokes 55 within the upper ends of the standards. The glass tray 60 is positioned on the yokes 55, as shown in Fig. 1, accidental displacement of the tray 60 being prevented by the return bent portion 56 of the yokes 45 55. If desired, the standards 44 can be used to support longitudinal partitions 15, the partitions being inserted into the slot 50 of the tubular extension 48 and forced downwardly between the vertical walls 47 50 of the standards 44.

It is seen that I have provided a simple, inexpensive apparatus for forming compartments on display counters, and that the apparatus of my invention is very flexible and durable and can be assembled very easily.

What I claim is:

1. In combination with a display counter: a plurality of inverted pans placed on the top of said counter; a plurality of partitions 60 vertically supported between said pans; and locking means engaging said pans, said locking means securing adjacent pans in supporting relation with said partitions and locking said partitions from removal end 65 wise from between said pans.
2. In combination with a display counter: a plurality of inverted pans on the top of said counter; a plurality of partitions vertically supported between said pans; and locking means engaging said pans, said locking means securing adjacent pans in supporting relation with said partitions, said locking means being held in locking engagement with said pans by said partitions. 70
3. In combination with a display counter: an inverted pan positioned on said counter; a partition on said pan; a partition supporting clip provided at each end of said partition; and locking means on said clips engaging said pan to prevent lateral or vertical movement of said clips on said pan, said clips being held in said interlocking engagement with said pan by said partition. 75
4. In combination with a display counter: an inverted pan positioned on said counter, said pan having apertures on the top side thereof; a partition on said pan; a partition supporting clip provided at each end of said partition; and locking means on said clips, said locking means being received by said apertures and interlocked with said pan in response to relative horizontal movement of said clips and said pan, said clips being held in said interlocking relation by said partition when the latter is supported between said clips. 80
5. In combination with a display counter: a plurality of inverted pans placed side-by-side on the top of said counter; a plurality of transverse partitions supported between said pans; a plurality of longitudinal partitions supported on top of said pans in transverse relation with said transverse partitions; a plurality of clips; and means on said clips engaging with said pans, certain of said clips locking adjacent pans in supporting relation with said transverse partitions and certain other of said clips supporting said longitudinal partitions on said pans, all of said clips being held in interlocking engagement with said pans by contact with the ends of said longitudinal and said transverse partitions. 100
6. In combination with a display counter: a plurality of inverted rectangular pans placed side-by-side transversely on the top of said counter, the top surfaces of said pans being provided at each corner thereof with an aperture, said top surfaces also being provided with rows of equally spaced apertures positioned parallel to and in close proximity with the longer sides of said top surfaces; transverse partitions supported between said pans; longitudinal partitions supported on the top of said pans in right-angled relation with said transverse partitions; a partition supporting clip provided at each end of each of said transverse and longitudinal partitions; and a pair of hooks 110
- 115
- 120
- 125
- 130

- extending downwardly from each of said clips, said hooks being received by suitable pairs of the aforesaid apertures. engagement with said pans by said partitions.
7. In a display counter the combination of: a four-sided metal pan placed bottom-side-up on a counter, said pan being provided on its uppermost surface with a plurality of equally spaced apertures; a pair of clips; vertical opposed walls provided on each of said clips; a horizontal base provided at the lower edges of said walls; and a pair of depending hooks downstruck from said base, said hooks being adapted to be received by a pair of said apertures in said pan, said clips being locked to said pan by engagement of said hooks with the top of said inverted pan, said clips and said pan being adapted to cooperatively support a partition.
- 10 8. In a display counter the combination of: a four-sided metal pan placed bottom-side-up on a display counter, said pan being provided on its uppermost surface with a plurality of regularly spaced apertures; a standard perpendicularly supported by said pan; a horizontal base provided on said standard; a pair of depending hooks downstruck from said base, said hooks being received into interlocking engagement with said pans by a pair of said apertures; vertical opposed walls extending upwardly from said base; a post extending upwardly from the top of said walls; and a horizontally disposed yoke removably secured to the upper end of said post, said standard being adapted to support a partition on said display counter and an elevated tray in vertical spaced relation with said display counter.
- 15 9. In combination with a display counter: a plurality of inverted pans placed on the top of said counter; a plurality of partitions supported between said pans in transverse relation with said counter; a plurality of standards; locking means provided on the lower ends of said standards, said locking means securing adjacent pans together in supporting relation with said partitions; and means provided on the tops of said standards for supporting a horizontal tray in elevated relation with said counter.
- 20 10. In combination with a display counter: a plurality of inverted pans placed on the top of said counter; a plurality of partitions supported between said pans in transverse relation with said counter; a plurality of standards; locking means provided on the lower ends of said standards, said locking means locking adjacent pans together in supporting relation with said partitions; and means provided on the tops of said standards for supporting a horizontal tray in elevated relation with said counter,
